UNITED STATES PATENT OFFICE.

CARROLL W. PROCHASKA, OF NEW YORK, N. Y., ASSIGNOR, BY MESNE ASSIGNMENTS, TO ACTUS CARBURETOR & MANUFACTURING CO., INC., A CORPORATION OF NEW YORK.

CARBURETER.

1,240,876.

Specification of Letters Patent. Patented Sept. 25, 1917.

Application filed August 4, 1915. Serial No. 43,530.

To all whom it may concern:

Be it known that I, CARROLL W. PROCHASKA, a citizen of the United States, residing at 508 W. 122nd St., N. Y. C., in the State of New York, have invented certain new and useful Improvements in Carbureters, of which the following is a specification, reference being had to the accompanying drawings, forming a part hereof.

This invention relates to carbureters and has for its general objects to improve the construction and operation of such devices and increase their efficiency under all conditions of operation of the motor. More particularly, the invention seeks to overcome many objections which are found in carbureters of known type and to meet the deficiencies of such carbureters by including devices which not only perform functions now known but, in addition, operate in such time relation to one another as to bring about a coördination demanded by the principles of physics for the most efficient operation of carbureters. In accordance with the invention, account is taken of the relatively restricted area of the gasolene supply duct and the relatively large area of the port for the air supply whereby the volumetric proportions of gas and air under changing pressures are very different from such volumetric proportions under normal running conditions, by reason of the restricted gasolene passage. Compensation has been made for the disproportionate supply of air to the mixing chamber at the instant of changes in pressure therein, as is the condition in known carbureters by providing actuating devices for the needle valve and the air valve which automatically cause the air valve to lag behind the gasolene valve upon initiation of movement of the latter. In this way the normal relative areas of the gasolene port and the air port are always altered upon initiation of movement of the gasolene valve so that the area of the gasolene port is increased before the area of the air port is increased to a corresponding degree. In known structures, where the gasolene and air valves move in harmony, the force opposed by the restricted gasolene duct to an increased flow of gasolene is so great that an increase in the volume of air is not accompanied immediately by a corresponding increase in the volume of gasolene and a lean mixture is taken into the

motor. The improved structure, as suggested above, overcomes this condition and insures a substantially fixed volumetric ratio between the gas and air at all times.

Figure 1 is a view in vertical section taken through the improved carbureter.

Fig. 2 is a view, partly in section and partly in plan, taken on the plane indicated by the line 2—2 of Fig. 1 and looking in the direction of the arrows.

Fig. 3 is a view in section taken through the float chamber on the plane indicated by the line 3—3 of Fig. 1 and looking in the direction of the arrows, the other parts of the carbureter being omitted.

The casing *a* of the improved carbureter has formed therethrough at its central portion a passage in which is disposed a Venturi tube *b* into which air is drawn for low speed from an air passage *c* and in the constricted portion of which is introduced gasolene through a gasolene duct *d* communicating with a gasolene reservoir *e* which is in communication with the float chamber *f*. The low speed air derived through the air passage *c* commingles with the gasolene withdrawn through the duct *d* by the suction of the engine at the constricted part of the Venturi tube *b* and is drawn upward into a mixing chamber *g* into which air for high speed is drawn by the suction of the motor, and the mixing is effected in this chamber prior to its passage past the butterfly valve *h* to the motor, as is usual. The first feature of the invention is concerned with the control of the port area of the gasolene duct *d* and the port area of the main air supply for the mixing chamber *g*, the air being drawn into the mixing chamber past the air valve indicated at *l* and to which specific reference will be made hereinafter. The gasolene duct *d* is controlled by a high speed traveling needle valve *i* which may be adjustably mounted in a threaded sleeve *k* which is supported rotatably in the casing *a* of the carbureter and supports the needle valve in proper relation to the mouth of the duct *d*. The sleeve *k* which rotates in the casing *a* and carries with it the needle valve *i* and imparts axial movement to the latter, is connected through a swiveled pin *k'*, link *k*² and a second swiveled pin *k*³ secured to the other end of the link, to the supporting shaft *h'* for the butterfly valve *h*. The connection described permits universal move-

ment between the shaft h' and the rotatable sleeve h so that actuation of the shaft by any usual devices results in simultaneous rotative movement of the sleeve h and axial movement of the needle valve i . It will be evident to the skilled mechanic that other means for effecting the desired relative movement of the butterfly valve h and the needle valve i can be employed, the invention not being limited to the precise means for bringing about such relative movement. Other devices, now to be described, are interposed between the butterfly valve h and the air valve l so that movement of the butterfly valve with the needle valve i , in the manner described, will bring about, in the phase relation hereinafter pointed out, movement of the air valve. In the illustrated embodiment, the air valve l is shown as carried on a tubular shaft l' which, in turn, is mounted slidably on a fixed shaft m supported in the casing a of the carbureter. Guided on the tubular shaft l' and preferably disposed within the mixing chamber g , so as to be protected thereby, is a grooved collar n which is held yieldingly against axial movement by spiral springs o and p interposed, respectively, between the collar and the air valve l and a flange l^2 formed on the lower end of the shaft l' . This collar is engaged operatively by a bell crank lever q supported pivotally on a suitable bearing post a' secured to the carbureter casing a and the free end of the bell crank lever q is connected to the butterfly valve h through a link q' secured pivotally to the face of the butterfly valve and to the bell crank lever. From the description given, it will appear that movement of the butterfly valve h causes movement of the air valve l through the link q' and one or the other of the springs o , p , according to the direction of movement of the valve. In the improved construction, the yielding connection just described is provided in order that the movements of the valve l will lag slightly behind the movements of the butterfly valve h and the needle valve i . This phase relation in the movements of the elements referred to is insured by a dash pot action effected by securing to the shaft l' a disk or piston l^3 which has a sliding fit in a cup or cylinder a^2 carried on the carbureter casing or some removable section thereof. In order to afford the greatest possible degree of accessibility to all of the elements just described for purposes of adjustment, replacement or repair, the air port in the mixing chamber g is really formed as a ring a^3 which is screw threaded into the casing a of the carbureter and receives with a sliding air-tight fit the air valve l . With this ring may be formed arms a^4 which permit the free passage of air through the ring when the valve

is open and carry on their upper ends the cylinder a^2 for the purpose explained. By removing the ring a^3 , the valve l and all the associated mechanism just described may be disassembled and removed.

The valves and their connections having been described in some detail, it will be well to point out the theory of operation on which the structure is based in order that the advantages derived in a device of this character may be appreciated. The force opposed to any change in the rate of flow of gasoline through the restricted duct d is very great, while the supply of air for the gasoline is always permitted to flow into the mixing chamber g through a relatively large opening. Accordingly, if the area of the duct d is suddenly increased and the relative area of the air port simultaneously increased, the volume of air in the mixing chamber will immediately be proportional to the extent of the valve opening, whereas the volume of gasoline drawn into the mixing chamber would, at the instant of increase of the port area, be far less than that normally derived from the given area, due to the restricted mouth. This condition, which is to be found in known carbureters, results in the induction to the motor of a lean mixture upon every change in position of the valves. In the present construction movement of the needle valve i is not accompanied by corresponding movement of the air valve l but this last named valve lags behind the needle valve so that the intended volume of gasoline for any given port opening is permitted to flow into the mixing chamber before the corresponding volume of air is admitted. This coördination is essential to the development of the highest degree of efficiency in a carbureter since through it, the relative proportion of air to gas for a combustible mixture of the proper character, is maintained under all conditions of operation.

No reference has been made in the preceding description of the air valve l to the specific character thereof inasmuch as the features upon which stress has been laid are not to be limited to the specific form of the air valve. However, it has been found in practice that excellent results may be obtained in the new carbureter by forming the valve l as a cylinder with a scalloped or saw-tooth wall. As shown in Fig. 1, the wall l^4 of the valve body has V-shaped recesses formed in the edge so that as the valve is moved downward in the ring a^3 the restricted portions of the recesses first pass the lower edge of the ring and establish communication between the mixing chamber g and the surrounding atmosphere. As the valve continues this downward movement, the width of the recesses and the volume of the openings through which the air passes increases,

not in a fixed ratio but in a variable and increasing ratio, as has been found to be most desirable in carbureter practice, it being well understood that the proportion of air to gas 5 may well be increased as the volume of fuel fed to the motor is increased. This result is secured by the form of valve illustrated. The float chamber is provided with a removable cover a^6 in which is formed a supply duct a^7 for gasoline which may be in communication with the source of fuel supply, as will be understood. The duct a^7 is controlled by a needle valve w which may be carried on a lever r pivoted to the inner face 10 of the cover a^6 and split at its free end to receive in frictional engagement a set screw r' which rests on a rigid arcuate plate s extending loosely through a slot t formed in a vertically disposed tubular guide t' for the float u . The lever arm r extends into the tubular guide t' through a slot t^2 formed in the wall thereof, so that the set screw r' may rest loosely on the arcuate plate s and thereby determine the position of the 15 lever arm r and the needle valve w . The plate s is held against accidental displacement in the tubular guide t' by means of suitable studs s' extending laterally from its faces and disposed without the tubular 20 guide, the free end of the plate s being arranged so as to rest directly on the upper face of the float. In this way, movement of the float u under changing levels of the liquid within the chamber a^5 is communicated directly to the plate s and from it to the needle valve w through the lever arm r . However, it will be appreciated that it is desirable under different conditions to make an initial adjustment between the float 25 u and the needle valve w so that the desired liquid level may be secured. This initial adjustment may be effected readily in the illustrated embodiment by forming an opening a^8 in the cover a^6 directly above the head 30 of the adjusting screw r' so that, upon removal of the screw cap a^9 from the opening a^8 , a suitable tool, such as a screw driver, may be inserted through the opening and engaged with the screw and axial movement of 35 the latter effected so as to change the fixed relation between the float u and the needle valve w in a manner which will be evident. By moving the screw r' upward in an axial direction, the liquid level is raised in the 40 float chamber, while contrary movement of the screw r' serves to bring about an adjustment which will insure a lower liquid level in the chamber. The adjustment just described is especially desirable where the 45 liquid within the float chamber a^5 is kept under an appreciable pressure, as is usually the present day practice and is especially useful in combination with the lever arm r whereby the force transmitted from the 50 rising float u to the needle valve w is multi-

plied appreciably and a more certain regulation of the fuel supply thereby secured.

It will be noted that the tubular guide t' which extends centrally through the annular float u is maintained in position by bosses a^{10} and a^{11} formed respectively in line with the guide on the bottom of the float chamber a^5 and on the inner face of the cover a^6 so as to enter the guide when the parts are assembled.

A further feature of the improved float chamber and associated devices resides in the simple construction of the plate s by which the movement of the float u is communicated directly to the controlling devices for the needle valve w . This plate s , as mounted in the tubular guide t' , has limited free play in the guide so that it adapts itself automatically to changing positions of the carbureter and yet serves under all conditions to transmit the movements of the float.

From the float chamber a^5 the gasoline flows through a passage a^{12} to the reservoir e from which it is withdrawn through the high speed supply duct d in the manner pointed out. In a carbureter of this type, it is desirable to provide an auxiliary gasoline supply passage through which a limited amount of gasoline passes directly into the mixing chamber, by the suction of the motor. Such a passage has been shown at v in Fig. 1 and comprises conveniently a single tubular member which is threaded into the lower wall of the casing of the carbureter and extends through the reservoir e into the mixing chamber g and places the reservoir in communication with the chamber by openings v' formed in its lower end to receive gasoline and by a restricted opening v^2 formed in its upper end and disposed within the mixing chamber at a level above the normal level of gasoline. This passage insures that a limited quantity of gasoline will be drawn from the mouth v^2 of the tube by suction of the motor, thereby supplying a supplemental quantity of gasoline which is not only useful as a starting charge but also during normal operation of the motor.

The operation and function of the several elements having been pointed out in connection with the detailed description of each and their coördinate operation having been particularly referred to where novel results are secured by such coördination, it is unnecessary to enter into a separate description of the operation of the carbureter as a whole. It is to be noted, however, that changes in the details of construction of many of the parts and rearrangements thereof may be made by those skilled in the art without departing from the spirit of the invention, the scope whereof is to be determined by the appended claims.

I claim as my invention:

1. In a carbureter, the combination with

- the gasoline duct and the air port, of valves controlling the duct and the port respectively, a single means actuating said valves, a yielding connection between the said actuating means and the air valve, and a positive connection between said actuating means and the gasoline valve, whereby movement of the gasoline valve is followed by movement of the air valve.
- 10 2. In a carbureter, the combination with the gasoline duct and the air port, of valves controlling the duct and the port respectively, a butterfly valve to control the flow of fuel to the motor, a positive connection 15 between the butterfly valve and the gasoline valve, and a yielding connection between the butterfly valve and the air valve, whereby movement of the butterfly valve causes corresponding movement of the gasoline valve and is followed by movement of the air 20 valve.
3. In a carbureter, a valve to control the gasoline, an air valve, a mixing chamber, a butterfly valve to control the flow of fuel from the mixing chamber, a positive connection between the butterfly valve and the gasoline valve, and a yielding connection between the butterfly valve and the air valve 25 extending through the mixing chamber and including a stem for the air valve, a collar mounted on the stem, opposed springs seated on the collar and expanding operatively against the valve, and a link connection between the butterfly valve and the collar. 30
- This specification signed this 2nd day of 35 July, A. D. 1915.

CARROLL W. PROCHASKA.
